UNITED STATES PATENT OFFICE.

FRANZ YOKEL, OF MERIDEN, CONNECTICUT, ASSIGNOR TO THE MERIDEN BRONZE COMPANY, OF SAME PLACE.

DESIGN FOR A SLAB FOR TABLE-TOPS.

SPECIFICATION forming part of Design No. 23,202, dated April 17, 1894.

Application filed March 5, 1894. Serial No. 502,448. Term of patent 3½ years.

To all whom it may concern:

Be it known that I, FRANZ YOKEL, of Meriden, in the county of New Haven and State of Connecticut, have invented a new Design for 5 a Slab for Table-Tops, (Case B;) and I do hereby declare the following, when taken in connection with the accompanying drawing and the letters of reference marked thereon, to be a full, clear, and exact description of the same, 10 and which said drawing constitutes part of this specification and represents a top or face view of a slab for a table-top illustrating the design.

This invention relates to a design for a slab 15 for a table-top, and the design consists in the configuration and ornamentation as shown in the accompanying illustration. The central portion of the slab is circular, and is surrounded by a border consisting of a series of

shell ornamentations A, surrounding a plain 10 panel, and surmounted by scroll work, alternating with ornate open scrolls B, the scrolls of the two ornamentations connecting at points, and the spaces between them filled by fret-work C, all springing from a beaded inner 25 border D, as shown in the accompanying illustration.

I claim—

The design for a slab for table-tops as herein shown and described. 30

In testimony whereof I have signed this specification in the presence of two subscribing witnesses.

FRANZ YOKEL.
